DESIGN FOR A HAT

William C. Gray, St. Charles, Ill., assignor to Jesse B. Hawley, Geneva, Ill.

Application October 4, 1935, Serial No. 58,832

Term of patent 14 years

To all whom it may concern:

Be it known that I, William C. Gray, a citizen of the United States and residing at St. Charles, county of Kane, and State of Illinois, have invented a new, original, and ornamental Design for a Hat, of which the following is a specification, reference being had to the accompanying drawing, forming a part thereof.

Fig. 1 is a top plan view of a hat embodying my design;

Fig. 2 is a side view in elevation of the same;
Fig. 3 is a fragmentary end elevational view of the same; and,

Fig. 4 is a fragmentary sectional view taken in a plane represented by line 4—4 in Fig. 1 of the drawing.

I claim:

The ornamental design for a hat substantially as shown.

WILLIAM C. GRAY.
